(Cl. D34—11)

To all whom it may concern:

Be it known that I, Jack Bloch, a citizen of the United States, residing at Leominster, Worcester County, and State of Massachusetts, have invented a new, original, and ornamental Design for a Coin Bank, of which the following is a specification, reference being had to the accompanying drawing, forming part thereof, in which:

Fig. 1 is a front elevational view of a coin bank, showing my new design;

Fig. 2 is a side elevation of the coin bank shown in Fig. 1;

Fig. 3 is a top plan view thereof; and,

Fig. 4 is a bottom plan view thereof.

I claim:

The ornamental design for a coin bank, substantially as shown.

JACK BLOCH.
